PAGE 2

Fig.3.

Fig.4.

Fig. 5.

Fig. 1 is a front elevational view of a clock embodying my new design;

Fig. 2 is a side elevational view;

Fig. 3 is a rear elevational view;

Fig. 4 is a top plan view with the ornamentation surrounding the dial face being omitted for convenience of illustration; and

Fig. 5 is a front perspective view thereof.

I claim:

The ornamental design for a clock or similar article, substantially as shown and described.
